HEEL ATTACHING MACHINE

Horace Grewcock, Leicester, England, assignor to United Shoe Machinery Corporation, Paterson, N. J., a corporation of New Jersey

Application July 25, 1934, Serial No. 736,841
In Great Britain September 6, 1933

15 Claims. (Cl. 1—32)

This invention relates to the attaching of heels by machine to shoes, and is particularly but, by no means exclusively, concerned with the attaching of wood heels to women's shoes by fasteners, usually nails, driven from inside the shoe.

In attaching wood or other high heels to women's shoes, it is usually desirable to hold the heel on the shoe by members which contact not only with the tread of the heel but with its side and rear surfaces, owing to it being difficult to apply sufficient heel-clamping pressure to the tread alone without incurring great liability of breaking the heel. As the height of heels increases, so the center height-line of the heel, measured from the middle of the tread surface to the middle of the heel-seat-end of the heel, assumes a decreasing angle with the general plane of the heel-seat of a shoe. In other words, the angle between the tread and heel-seat-surfaces of the heel increases with the height of the heel. This angle may be as much as 30 degrees. If pressure is applied to such a high heel by means of a tread-abutment which moves vertically downwards towards the jack or shoe-entering support, it tends to cant the heel and make it difficult to obtain a close joint between the rear of the heel and the upper of the shoe.

To provide a cure for the difficulties above indicated, a feature of the invention resides in the provision, in a heel-attaching machine, of a heel-tread-abutment which is arranged to receive thrust along a defined path to apply pressure to the tread of a heel, but in applying such pressure moves along a path which differs from the said defined path and preferably is adjustable so as to be made substantially vertical to tread-surfaces of differing heels.

There is disclosed herein means for limiting the clamping pressure applied to the tread-surface of the heel. This is not a part of the present invention, being made the subject of an application for Letters Patent of the United States, filed in the names of William R. Barclay and Frank Barton on July 25, 1934, its serial number being 736,882.

The above and other features of the invention will become apparent from a consideration of the following description, given by way of example and with reference to the accompanying drawings of a convenient construction according to the invention, in which drawings,

Fig. 1 is a side view of the upper part of a heel-attaching machine fitted with heel-holding mechanism according to the invention;

Fig. 2 is a front view of some parts of Fig. 1; and

Fig. 3 is a side view, partly in section and on a larger scale, of a portion of Fig. 2.

The invention may be embodied in any usual form of heel-attaching machine in which there is relative movement between a heel-abutment and a shoe-entering jack or similar member, for instance a machine as shown in British Patent No. 339,935, to the British United Shoe Machinery Co., Ltd. A heel-abutment head or housing 12 is arranged for movement along a vertical path to clamp a heel, being mounted at the bottom of a plunger 14 which slides in a vertical bore in an overhanging part of a heel-attaching machine frame 10. In the head 12 is mounted a stem 16 which operates a tread-face-engaging device or abutment 18, this stem 16 engaging the forward end of a compensating lever 20, the rear end of which acts upon an abutment 22 for the rear surface of the heel. The rear abutment 22 is normally biased upwardly by a light spring 23, pushing the tread-abutment stem 16 downward. Engaging the lever 20, and forming a movable pivotal point therefor, are two transverse levers 24 (Fig. 2) which operate heel side abutments 26.

In the present construction, the tread-face-engaging abutment 18 is carried upon a block 30 mounted upon a pair of arms 32 which are pivoted at their inner ends to the machine column 10. The abutment 18 is angularly adjustable on the block 30 by a hand-worm 33 which meshes with a worm-segment formed on said abutment. The block is fixed in different positions along the arms 32 by screws 35 which pass through slots in the arms so that the distance of the abutment from the column, and therefore from the back of a shoe located on a shoe-entering member or jack 40 (Fig. 1), may be adjusted. The arms are arranged for pivotal connection to anyone of an upwardly and outwardly inclined series of openings 36, 37, 38 (Fig. 1) in a block 39 fixed to the column 10. The upper face of the block 30 contacts with a partly spherical knob or contact member 42 on the under side of an adjustable inner stem-piece 43 threaded into the stem 16. The knob 42 has a flat under side relatively to which the block 30 slides when the main abutment-head 12 descends to clamp a heel.

The pivot-point of the arms 32 is adjusted upwardly or downwardly to one or another of the openings 36, 37, 38, according to the height of the heel being attached, in such a manner that the block 30 presents the abutment 18, when the

head 12 is moved down, with its under side substantially parallel to the tread-face of the heel. The abutment actually moves to heel-clamping position along an arcuate path the radius of 5 which is represented by the arms 32. The final movement along this path is substantially perpendicular to the heel-tread-face. The block 30 is maintained normally raised by a tension-spring 44, the connections for which will be later described, so that it always remains in contact with the knob 42. There have been described two 10 separate adjustments which alter the position of the block 30 and the abutment 18. First, movement of the block 30 along the arms 32 by the worm 33 alters the effective length of the arms 15 and the radius of the path of the block, and, second, application of the pivot of the arms to one or another of the openings 36, 37, 38 changes the position of the center of the path. The upper 20 pivotal opening 36 will be employed when extra-high heels (more than $3\frac{1}{2}$ inches, say) are to be attached to shoes. As shown, the center opening 37 may be employed for heels up to that height, although the upper point may be used for heels of any greater height than three 25 inches. The lower opening 38 will be used for heels of less than two inches in height, it being generally desirable to locate the lower surface of the block 30, when down, as close to parallelism 30 with the tread-face of the heel as possible, avoiding excessive angular adjustment between the block and the abutment 18, that shown in Figs. 1 and 3 being an approximate maximum. The inner stem-piece 43 may be adjusted vertically 35 relatively to the housing 12 by a hand-wheel 45 (Fig. 1) which is connected by a rod 41 (Fig. 3) to the stem 16. Rotation of the stem 16 by the wheel 45 causes the member 43, which is kept from rotating by a guide 49, to be screwed either 40 in or out of the stem 16. The abutment 22 is self-adjustable with reference to the rear surface of a heel, it being movable in a circular guideway in its holder 25. This holder is horizontally adjustable by a hand-screw 29 relatively 45 to its carrying stem 31, which is engaged by the rear end of the lever 20. By its adjustments, the block 30 may be set to seat the abutment 18 accurately upon and to move substantially perpendicularly to tread-surfaces of heels of widely varying 50 height and pitch, such accurate seating being specially desirable when the heels are highest.

To limit the pressure which is to be applied to a specified part of a heel, the forward ends of the arms 32 are connected by a cross-piece 46 to a rod 48 which extends vertically to a slide-plate 50 mounted within a fixed guideway 52 formed upon the front face of the overhanging part of the machine-frame 10 in which the abutment-plunger 14 is guided. The plate 50 is pulled upwardly by the spring 44, above mentioned, and has ratchet-teeth on its opposite sides engaged by two pairs of pawls 54, 56 pivoted upon the guideway 52. The levers 24, which operate the side abutment members 26, have fixed to them upwardly extending arms 60 (Fig. 1) connected by a spring 62, which tends to hold the members 26 raised and apart from one another. The levers 24 also carry at the forward ends of their pivots upstanding fingers 64, having horizontal 65 tensions which are adapted to engage tail-pieces of the pawls 54, 56 in such a manner that when the abutment members 26 receive their first movement towards a heel, the fingers 64 are moved laterally away from the pawls and release them. Therefore, one or another of the pawls 70

engages, under the pull of tension-springs 66, 68, a tooth on the ratchet on one side or the other of the plate 50. The teeth on one side of the plate are cut so as to lie vertically between the teeth on the other side, to give a locking action 5 at half the distance between the teeth on either side. Also of the pairs of pawls on either side of the plate 50, one pawl is farther above its pivot by the distance of one quarter of a tooth than the other. Thus, locking can be insured at quarter-tooth distance. When a pawl engages the plate 50, the arms 32 and the tread-abutment 18 carried by them become locked against downward movement, and further descent of the abutment-housing 12, either by action of the machine-operator through a treadle, or under power of the machine applied automatically before the nails are driven to fasten a heel to a shoe, results solely in further depression of the rear and side abutments. The amount of pressure 20 that will be applied to the tread-surface of a heel by mechanism arranged as just described may be determined and regulated by adjusting the pull of the spring 62 which tends to hold the side abutment members 26 apart. This adjustment 25 may be effected by joining the spring to one of the arms 60 by an eye bolt 70, which may be varied as to its projection through the arm by turning the nut.

When a heel is clamped by moving towards 30 it the abutment-housing 12 containing members operating as above described, the abutment 18 will first engage the tread of the heel. As soon as this has occurred, further movement of the housing 12 causes the compensating lever 20 to 35 rock, its front end moving upwardly relatively to the housing, and the rear abutment 22 to move down into contact with the rear of the heel. Any further rocking movement of the lever 20 is then prevented by the seating of the rear member 22 40 on the heel, and downward movement of the housing 12 continues while the lever 20 remains at rest. Consequently, the side abutment members 26 are moved in against the heel because the inner ends of their levers 24 are within the 45 lever 20. At this time, the tread-abutment 18 becomes locked by the engagement of a pawl 54 or 56 with the ratchet-plate 50, and further downward movement of the housing increases only the pressure applied to the heel by the rear 50 and side abutments. The pawls 54 and 56 are forced by the fingers 64 out of engagement with the ratchet-plate, when the side abutments return with the housing to their original positions after a heel has been attached.

Having described the invention, what is claimed as new and desired to secure by Letters Patent of the United States is:

1. In a heel-attaching machine, a heel-tread-abutment, means for applying pressure to the abutment along a defined path, and means made effective by the application of such pressure for producing movement of the abutment along a path different from said defined path.

2. In a heel-attaching machine, a heel-tread-abutment, means for applying pressure to the abutment along a defined path, means made effective by the application of such pressure for producing movement of the abutment along a path different from said defined path, and means arranged to vary the angles between the paths.

3. In a heel-attaching machine, a support for a shoe and a heel to be attached, a pressure-head movable toward and from said support in a direction other than perpendicular to the 75.

- tread-surface of the supported heel, and a tread-abutment movable by the pressure-head in a direction substantially perpendicular to said tread-surface.
5. 4. In a heel-attaching machine, a support for a shoe and a heel to be attached, a pressure-head movable toward and from said support in a direction other than perpendicular to the tread-surface of the supported heel, a tread-abutment movable by the pressure-head in a direction substantially perpendicular to said tread-surface, and means arranged to vary the angle at which the tread-abutment is moved by the pressure-head.
10. 5. In a heel-attaching machine, a movable pressure-head, a tread-abutment movable by the head, and connections from the tread-abutment to a point fixed against movement to modify the movement of the abutment.
15. 6. In a heel-attaching machine, a movable pressure-head, a tread-abutment movable by the head, connections from the tread-abutment to a point fixed against movement to modify the movement of the abutment, and means arranged to vary the point of attachment of the connections.
20. 7. In a heel-attaching machine, a frame, a pressure-head movable thereon, a contact member carried by the head, an arm pivoted upon the frame, a block variable in position upon the arm, a tread-abutment variable in position upon the block, and means for holding the block in engagement with the contact member.
25. 8. In a heel-attaching machine, a frame, a pressure-head movable thereon, a contact member carried by the head, an arm pivoted upon the frame, a lock variable in position upon the arm, means arranged to move the block along the arm, a tread-abutment variable in position upon the block, means arranged to move the abutment angularly upon the block, and a spring joining the arm to the frame and acting to draw the block against the contact member.
30. 9. In a heel-attaching machine, a frame, a jack mounted upon the frame for supporting a shoe and a heel to be attached, a pressure-head movable upon the frame, an arm pivoted upon the frame and extending above a heel upon the jack in co-operation with the pressure-head, and a heel-tread-abutment mounted upon the arm and co-operating with the jack.
35. 10. In a heel-attaching machine, a frame, a jack mounted upon the frame for supporting a shoe and a heel to be attached, a pressure-head movable upon the frame, an arm pivoted upon the frame and extending above a heel upon the jack in co-operation with the pressure-head, a heel-tread-abutment mounted upon the arm and co-operating with the jack.
40. 11. In a heel-attaching machine, a frame, a jack mounted upon the frame for supporting a shoe and a heel to be attached, a pressure-head movable vertically upon the frame, an arm pivoted upon the frame and extending above a heel upon the jack in co-operation with the pressure-head, a heel-tread-abutment movable upon the arm and co-operating with the jack, and means arranged to fix the abutment in different positions longitudinally of the arm.
45. 12. In a heel-attaching machine, a frame, a jack mounted upon the frame for supporting a shoe and a heel to be attached, a pressure-head movable vertically upon the frame, an arm pivoted upon the frame and extending above a heel upon the jack, said arm being movable by the pressure-head, a heel-tread-abutment movable upon the arm, and means arranged to fix the abutment in different angular positions upon the arm.
50. 13. In a heel-attaching machine, a frame, a jack mounted upon the frame for supporting a shoe and a heel to be attached, a pressure-head movable vertically upon the frame, an arm pivoted upon the frame and extending above a heel upon the jack, said arm being movable by the pressure-head, there being pivotal connections provided on the frame for the arm at points located along a line inclined to the vertical, and a heel-tread-abutment mounted upon the arm for co-operation with the jack.
55. 14. In a heel-attaching machine, a frame, a pressure-head movable thereon, a lever fulcrumed upon the head, pressure-abutments oppositely movable by the lever, and connections between one of the abutments and the frame to modify the movement of such abutment.
60. 15. In a heel-attaching machine, a frame, a pressure-head movable thereon, a lever fulcrumed upon the head, a tread-abutment and a rear abutment movable by the lever, movement-modifying connections between the tread-abutment and the frame, and means arranged to vary the projection of the tread-abutment from the lever.

HORACE GREWCOCK.
